UNITED STATES PATENT OFFICE.

CARL A. LARSON, OF OSWEGO, NEW YORK.

AUTOMATIC CAN-FILLING MACHINE.

1,141,561.

Specification of Letters Patent.

Patented June 1, 1915.

Application filed January 12, 1914 Serial No. 811,674.

To all whom it may concern:

Be it known that I, CARL A. LARSON, a citizen of the United States, residing at Oswego, in the county of Oswego and State of New York, have invented a new and useful Automatic Can-Filling Machine, of which the following is a specification.

An object of the present invention is to provide a machine which will fill cans, the amount of material deposited in each can being adjustable.

A further object is to provide a can filling machine which includes a plurality of revolving measuring compartments, the capacity of which may be varied, the compartments being mounted to move in an orbit so that the upper open ends thereof will register with openings extending through a hopper which provides for the filling of the measuring compartments, beneath which compartments the cans are automatically placed and remain until they have been completely filled, after which they are automatically moved from beneath the measuring compartments to make way for unfilled or empty cans.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferred embodiment of my invention is illustrated, in which—

Figure 1 is a top plan view of my improved can filling machine. Fig. 2 is a side elevation, parts appearing in section. Figs. 3 and 4 represent respectively in plan and in side elevation the lower rotating disk and the tubes carried thereby. Figs. 5 and 6 represent respectively in plan and in side elevation the upper rotating disk and the tubes carried thereby. Fig. 7 is a detail plan of the valve plate which temporarily closes the lower ends of the measuring compartments during the time they are being filled by the hopper. Fig. 8 is a detail plan of the bottom plate of the hopper and illustrating the arcuate slot therein whereby the

measuring compartments will be in communication with the hopper for a considerable period to insure the proper filling thereof.

Referring to the drawings in which similar reference numerals designate corresponding parts throughout the several views, a frame is provided and the same includes legs 9 between which extend braces 10 and upon the legs is mounted a top 11 which forms a support for the cans as they are revolved with the measuring compartments during the filling operation.

A vertical shaft 12 is mounted within suitable bearings 13 on the frame and the shaft projects up through the top 11. Upon the shaft 12 is rigidly secured a drum 14. The drum 14 is spaced above and out of contact with the top 11 and due to the manner in which the latter supports the cans it will hereinafter be termed a base. Spaced from the periphery of the drum 14 and concentric therewith is a retaining rim 15 which is rigidly secured to the base 11 by angle members 16. The rim 15 does not completely encompass the drum 14 but as illustrated at 17, is bent at one end in the arc of a circle, to define a can entrance 103. The rim 15 is also bent outwardly as at 18 to define a delivery outlet 104 for the cans after the same have been filled. The drum 14 is provided with eight outstanding fingers 19 which extend across the runway 102 defined by the drum and the rim 15. These fingers 19 are adapted to contact with the cans and force the same along the runway and through the delivery outlet 104 which is adjacent the outturned portions 18 of the rim 15.

Mounted upon and rigidly but adjustably secured to the shaft 12 by a set screw 20 is a lower disk 21 which is provided as illustrated in Fig. 3 with eight apertures 22 surrounded by upstanding tubes 23. The disk 21 is provided with a spider 24 by means of which it is mounted on the shaft 12. A second or upper disk 25 is also provided and the same includes a spider 26 which is adjustably secured by a set screw 27 to the shaft 12. The upper disk 25 is provided with eight apertures 28 surrounded by depending tubes 29. The tubes 29 are adapted to telescope within the tubes 23 of the lower disk 21. By the construction above described the lower disk 21 may be spaced vertically with regard to the base 11 to allow for cans of different heights. The capacity

of the measuring compartments defined by the telescoped tubes 23-29 may be adjusted by shifting the upper disk 25 along the shaft 12. The measuring compartments are 5 spaced above and located slightly in advance of the can revolving fingers 19 so that, as illustrated at the extreme left of Fig. 2, a can 30 when in contact with one of the fingers 19 and within the runway 102 10 will be positioned directly beneath one measuring compartment and will so remain throughout the orbital movement of the can. Thus material within the measuring compartments may pass directly into the cans, 15 which are disposed in co-axial relation to the compartments.

Mounted above and held in contact with the upper disk 25 is a hopper plate 31 supported by brackets 32, which as illustrated 20 in Fig. 2, are rigidly secured to the base 11. The hopper plate 31 as illustrated in Fig. 8, is provided with an arcuate slot 33 of a length approximately equal to the arc defined by three of the measuring compartments. 25 Mounted upon the hopper plate 31 is an upstanding hopper casing 34 in which is placed the material with which the cans are to be filled. In the ordinary use of the machine the contents of the hopper 31-34 30 is dry although moist material may be used. In this connection it will also be noted that the number of measuring compartments and can revolving fingers 19 may be varied without departing from the spirit of the invention. 35

Supported by the brackets 32 and in contact with the lower disk 21 is a valve plate 35 which constitutes a closure for the lower ends of the measuring compartments while 40 the latter are positioned beneath and being filled by the hopper 31-34. The stationary valve plate 35 is provided with a notch 36 which is positioned in the path of travel of the measuring compartments and provides 45 for a proper opening of the lower extremities of the compartments as they pass beyond the stationary plate 35. In this connection it is to be noted that the plates 31 and 35 are provided respectively with central arcuate notches 38 and 37 which receive for rotation the spiders which support the upper and lower disks. The plates 31 and 35 are adjustably mounted upon the brackets 32 as shown at 100, thus allowing 50 for the adjustment of the disks 21 and 25.

A can receiving magazine 39 is formed by a plurality of spaced vertical rods one of which is attached to the base 11 and all of which are connected to a ring 101 spaced 60 from the base 11. Into this magazine the cans are inserted one upon the other with the openings therein at the top. In order to feed the cans to the runway 102 defined between the drum 14 and the rim 15, a vertical shaft 40 is provided and the same is

supported in suitable bearings 41. The shaft 40 projects up through the base 11. A circular plate 42 is rigidly secured to the shaft 40 and projecting from the plate are wipers 43 which move transversely of the magazine 39 and advance the lowermost can along the arcuate portion 17 of the rim 15 and into the path of the can revolving fingers 19. The can will thus be carried along through the runway 102 and be 70 filled from the measuring compartment positioned directly thereabove and coaxial therewith. The measuring compartments as they move from above the valve plate 35 will discharge into the cans and as the cans 75 revolve about the shaft 12 as a center they will become filled and will be delivered from the runway 102. The cans are prevented from repeating the cycle by a guard 44 which extends above and below the path of 80 movement of the actuating fingers 19 and terminates adjacent the peripheral edge of the drum 14 so that as the can comes into forced contact with the guard, the can will be moved tangentially of the drum, and will 85 be advanced between the guard 44 and the part 18 of the rim 15 along the delivery outlet 104. The drive between the shafts 12 and 40 takes the form of a chain 45 and sprocket wheels 46.

A main driving shaft 47 is provided and the same is equipped at its outer extremity with a belt wheel 48. Interposed in the shaft 47 is a clutch 49 whereby the shaft may be intermittently or continuously rotated as desired. The shaft 47 drives the vertical shaft 12 by means of beveled gears 50 and the shaft (12) in turn drives the can feeding shaft 40. In order to control the machine further, a clutch 51 is interposed in the shaft 40 and is operated by means of a lever 52, the construction being such that the shaft 40 may be continuously or intermittently rotated with respect to the shaft 47.

Especial attention is directed to the fact that the plate 35 is provided with the notch 36 in one edge. Further, it is to be noted that the diameter of each compartment is slightly greater than the distance between the base of the notch 36 and one end wall of the hopper 34. Owing to this feature, the discharge from the compartment into the can will be initiated by the weight of the material in the hopper, thus assuring a prompt filling of the can. Recalling the comparatively inexpensive nature of the material handled by a device of this type, noting that extreme accuracy is not called for, and that the cans, ordinarily, as sold are not filled to the extreme top, and observing that any inaccuracies resulting from the procedure above outlined may be practically 115 done away with by elongating the compartments or shortening them, it will be obvious 120 125 130

that no serious disadvantages flow from the fact that, for a short period of time, a small but unobstructed passage exists directly from the hopper casing 34 through 5 the measuring compartment into the can. It is to be observed, further, that the notch 36 is of approximately semicircular form, thereby to effect a complete opening of the bottom of the compartment when the compartment and the can are partially beneath the plate 35, and consequently at an early stage in the cycle.

Having thus described my invention, what I claim is:—

15 In a can filling machine, a supporting frame embodying a base; a shaft journaled for rotation in the frame; a plurality of measuring compartments carried by the shaft; a shaft supported arm individual to 23 each compartment and constituting means for advancing cans along the base in vertical alinement with the compartments; a hopper beneath which a part of the com-

partments register at one time; and a frame supported plate forming a closure for the 25 lower ends of the compartments which are beneath the hopper, the plate having a notch in one edge and the diameter of each compartment being slightly greater than the distance between the base of the notch and 30 one end wall of the hopper, whereby the discharge from the compartment into the can will be initiated by the weight of the material into the hopper, the notch being of approximately semi-circular form thereby to 35 effect a complete opening of the bottom of the compartment when the compartment and the can are partially beneath the plate.

In testimony that I claim the foregoing as my own, I have hereto affixed my signature in the presence of two witnesses.

CARL A. LARSON.
